UNITED STATES PATENT OFFICE.

FREDERICK J. EDGARS, OF BROOKLYN, NEW YORK.

DESIGN FOR A WOODEN BOX.

SPECIFICATION forming part of Design No. 24,034, dated February 12, 1895.

Application filed January 17, 1895. Serial No. 535,279. Term of patent 7 years.

To all whom it may concern:

Be it known that I, FREDERICK J. EDGARS, a citizen of the United States, residing at Brooklyn, in the county of Kings and State 5 of New York, have invented a Design for a Round Wooden Box, of which the following is a specification.

The leading feature of this design for a round wooden box consists in the conical top, 10 bulging sides and intermediate rib and cove below the cone of the top.

In the drawings Figure 1, is an elevation partially in section, and Fig. 2, is a plan of the same.

The top of the box is conical at *a*, and the 15 cove *b*, intervenes between the rib *c*, and the base of the cone. The sides are bulging at *d*, and the rib *e*, and curved flange *f*, form the base.

I claim—

The design for a wooden box substantially 20 as described and shown.

Signed by me this 12th day of January, 1895.

FREDERICK J. EDGARS.
